UNITED STATES PATENT OFFICE.

WILLIAM A. DUNLAP, OF PITTSBURGH, PENNSYLVANIA.

METALLIC SHIPPING-CASE.

1,138,643.

Specification of Letters Patent. Patented May 11, 1915.

Application filed March 19, 1914. Serial No. 825,362.

To all whom it may concern:

Be it known that I, WILLIAM A. DUNLAP, residing at Pittsburgh, in the county of Allegheny and State of Pennsylvania, a citizen of the United States, have invented or discovered certain new and useful Improvements in Metallic Shipping-Cases, of which improvements the following is a specification.

10 It is the object of the invention to provide a metallic collapsible shipping case, which shall be of simple and light construction, consequently of small cost and easily handled, and at the same time durable, not 15 readily damaged or disarranged, and when the parts are assembled and locked together in their operative relation, the structure as a whole will be extremely rigid and strong.

15 In the accompanying drawings there is 20 shown a case embodying the invention in its preferred form.

Figure 1 is a perspective view of such a case. Fig. 2 is a central transverse sectional view of the case. Figs. 3-6 are details. 25 Figs. 7 and 8 are details, showing a slightly modified form of hinge. Fig. 9 is a transverse sectional view, and Fig. 10 a longitudinal sectional view, of the upper portion of a modified form of the case, and Figs. 11 30 and 12 details thereof. Fig. 13 is an edge view of the members of the case when folded together.

Referring first to Figs. 1-6, the body of the case is made up of the front and rear 35 vertical side walls A and B, and the end walls C and D. These walls are preferably each made up of a single metal sheet, which may be plane-surfaced as shown, or may have any suitable cross-sectional form. The 40 walls are hinged together at the corners of the case through the medium of the hinge-wires 1 and 2, which are bent about the edges of the front and rear walls A and B. At the corners of the case the sheets which form 45 the walls are provided with integral alternately arranged projecting tongues 3, 4, which are bent about the vertical portions of the hinge-wires, each tongue being then bent back upon the inner face of its respective 50 sheet, as shown in Fig. 5, and secured thereto by "spot welding" or otherwise. This forms what I term an anchored hinge, and I have found it to be of great advantage in imparting rigidity to the sheet metal walls. 55 At the top and bottom of the case the horizontal portions of the hinge-wires 1, 2, are

bent outwardly from the plane of the vertical portions of these wires, as shown at 5, Figs. 1 and 5, for a purpose to be herein-after indicated. At the top and bottom of 60 the case there are provided hinged members which are preferably of identical construction, one of which forms the cover of the case, and the other, for purposes of description, may be called the bottom. The rear 65 edge of the cover E and the upper edge of the rear side wall B are hinged to the upper horizontal portion of the hinge-wire 2 in the same manner as heretofore described, namely, by means of alternately arranged 70 integral projecting tongues, which are bent about the hinge wire and then secured to the respective body portions of wall and cover. The front edge of the bottom F and the lower edge of the front side wall A are 75 in like manner hinged to the lower horizontal portion of the hinge-wire 1. The upper and lower edges of the end walls C and D may be reinforced with wires if desired, but the case illustrated herein will be made 80 sufficiently strong by merely folding the metal of the edges of these end wall in any well known way.

The body portion 6 of the cover E is depressed so as to fit within the vertical walls 85 of the case, and an upstanding marginal rim 7 is formed about the depressed body portion, the edge of the rim projecting over the edges of the end walls and front side wall of the case. The edge of the rim is also 90 preferably bent downwardly so as to form a recess 8 underneath the rim, into which the edges of the said vertical walls of the case will project when the cover is closed, as shown in Figs. 1 and 2. The bottom is 95 preferably of the same form as the cover E. The inwardly set body portions of the cover E and bottom F add material strength and rigidity to the structure as a whole, and this effect is increased by bending the edge 100 of the rim, as described, so as to overlap the edges of the vertical walls.

At the top of the case at the front, the upper edge 9 of the wall A is beaded so as to inclose the upper horizontal portions of 105 the wire 1. But the wire 1 is cut away centrally at 10 and 11, as shown in Figs. 1 and 5, and within this top beaded edge 9 of the wall A, and between the opposite ends 10 and 11 of the wire 1, is arranged a locking-member 12 adapted to turn therein, which may also be made of wire. This locking- 110

member is provided with the integral loops 13 of any desired number, which project through elongated slots 14 provided for them in the beaded edge 9 of the wall A and 5 in the marginal rim 7 of the cover E. In swinging the cover on its hinges to the closed position shown in Fig. 1, the locking member 12 is turned so that these loops 13 point 10 upwardly and pass through the slots 14 in the cover. Then when the cover is closed, the locking member 12 is turned so that the loops 13 lie horizontally above the body portion 6 of the cover, and thus lock the cover in closed position. Under the central loop 15 of the locking member, a loop 15 may be formed in the body of the cover by slitting the metal and raising it slightly as shown in Figs. 3 and 5, so that a locking wire may be threaded through the members referred 20 to, and sealed in any suitable way, as indicated in Fig. 1 of the drawings.

The bottom F is, as has been said, preferably of the same construction as the cover E, being hinged at the lower edge of the 25 front of the case, and being locked at the lower edge of the rear wall of the case in the same way as above described.

Instead of using hinge-wires, as shown, and as is preferred, these may in some cases 30 be dispensed with, and a hinge such as is shown in Figs. 7 and 8 employed. Here one of the members 16 of the case is beaded at its edge, preferably by a double bead 17, and the other member 18 is provided with integral tongues 19 which pass through slots 20 in the member 16 and are bent around the bead 17, and are then bent back and anchored to the member 18 as previously described.

40 In Figs. 9-12, inclusive, the cover is shown as made up of a pair of flaps 20 and 21, which are hinged at the opposite sides of the case in the manner already described, and overlap each other along the central 45 line of the case. The two flaps are supported and secured together at the center by means of brackets 22 depending from the edges of the end walls, and carrying lock-

ing lugs 23 which project upwardly through slots in the flaps and provided with eyes 24 50 through which a wire may be passed. In this construction the upper edges of the end walls may be beaded about an inclosed wire, as shown in Fig. 10.

The described arrangement of the hinges 55 of the top and bottom members outside the vertical planes of the vertical wall members is of particular advantage, since it enables the top and bottom members to be folded back into flat bearing contact with the wall 60 members when the case is collapsed, as shown in Fig. 13.

I claim as my invention:

1. In a metallic packing case, the combination with vertical wall members hinged together at the corners of the case, of a top member hinged to the upper edge of one vertical wall member in a line outside the vertical plane of said wall member, and a bottom member hinged to the lower edge of the vertical wall member in a line outside of the vertical plane of said last mentioned wall member, said top and bottom members each having an inset body portion adapted to fit the opposite edge portions of said vertical wall members and thereby reinforce the structure against lateral strain.

2. In a metallic packing case, the combination with vertical walls, of a cover pivoted at the edge of one vertical wall, said cover having an inset body portion and an upstanding recessed rim, of a locking member carried by the opposite vertical wall and adapted to be turned inwardly from vertical to horizontal position, and an elongated slot in said upstanding rim adapted to receive the locking member when the latter is in vertical position and to permit it to be turned into horizontal position overlying the body portion of the cover.

In testimony whereof I have hereunto set my hand.

WILLIAM A. DUNLAP.
